UNITED STATES PATENT OFFICE.

CHARLES F. MATZ, OF DUBUQUE, IOWA.

HARROW.

Original application filed October 11, 1921, Serial No. 506,949. Divided and this application filed May 25, 1922. Serial No. 563,549.

To all whom it may concern:

Be it known that I, CHARLES F. MATZ, a citizen of the United States, residing at Dubuque, in the county of Dubuque and State 5 of Iowa, have invented certain new and useful Improvements in Harrows, of which the following is a specification.

This invention relates to spiral harrows, the present application being a division of 10 an application filed by me October 11, 1921, Serial No. 506,949.

In the annexed drawings, which illustrate the invention,—

Figure 1 is a plan view;

15 Fig. 2 is partly a side elevation and partly a longitudinal vertical section;

Fig. 3 is an enlarged section showing the axle mounting;

20 Fig. 4 is a perspective view of the mounting for the outer end of the harrow gang;

Fig. 5 is a similar view of the mounting for the inner end of the gang;

Fig. 6 is a detail section of the spoke.

The harrow frame comprises a draft bar 25 1 which is preferably a channel bar of suitable dimensions and to which, intermediate the ends thereof, is secured a cross bar or beam 2 consisting of an angle bar having one web or flange disposed vertically and 30 depending from the rear edge of the other flange or web. Angle bar braces 3 are secured at their front ends to the sides of the draft bar 1 at the front end thereof and are secured near their rear ends to the cross bar 35 or beam 2, as clearly shown. Secured to the cross bar or beam 2 at or near the ends thereof are clamping plates 4 which extend rearwardly and constitute supports for the pans or troughs 5 constituting the upper members 40 of the harrow gangs. These pans or troughs 5 are conveniently formed of channel bars and are adapted to receive large stones or other weights for the purpose of holding the gangs to their work. The pans or troughs 5 extend between the clamping plates 4 and the rear ends of the braces 3 and on the rear sides of the pans are secured brackets 6 which are metallic straps having their intermediate portions offset from their ends 45 whereby a slot or elongated space 7 is provided between the body of the strap and the pan to accommodate a bolt 8 inserted through the rear end of the adjacent brace 3 and the rear end of the corresponding 50 clamping plate 4 to retain the pan in proper

position. This arrangement applies the draft or propelling force to the rear side of the pan so that the harrow gang will be drawn over the field and at the same time permits the gang to be readily adjusted to 60 the desired angle to the line of draft and also permits it to have sufficient independent play in a vertical plane to readily pass over large stones or other obstructions which may be encountered. The inner ends of the pans 65 or troughs project under the draft bar 1 and are thereby held against rising to such an extent as would impair the efficiency of the harrow.

I also secure rigidly to each end of the 70 pan or trough, a pair of standards 14 which depend from the pan or trough and pass through the ends of a head or bearing block 15, being held therein by cotter pins or other fastenings fitted to the standards below the 75 bottom of the head. The heads are each provided with a central internally threaded opening 16 which receives the respective threaded end of the axle rod 17 and in the inner side of each head is an oil chamber 18 80 which is adapted to receive suitable absorbent packing to hold lubricant supplied thereto from a grease cup 19. At the inner end of the gang, the cup 19 is mounted in the head, as shown in Figs. 3 and 5, and the head is 85 provided with an annular rib or flange 20 on its inner side at its center to fit within the annular rim 21 of a bushing 22, the said rim constituting a dust cap to prevent accumulation of sand and dirt between the 90 bushing and the head. The bushing fits closely within the inner end of a sleeve or tube 23 upon which the spokes 24 are secured and the bushing is further provided with a lug or projection 25 fitting within a corresponding notch or recess in the end of the sleeve 23 and the hub 26 of the end spoke so that the bushing will revolve with the spoke and the sleeve, the axle rod 17 being held stationary by reason of its threaded connection with the heads 15, as will be readily understood. It will be readily noted that the lubricant from the cup 19 will be supplied to the end of the bushing and will work through between the axle rod and the 105 bore of the bushing so that free rotation will be insured. A similar bushing 27 is fitted in the outer end of the sleeve or tube 23 and is secured to the same and the hub 28 of the outer end spoke 29 by a lug 30 on 110

the bushing fitting within a notch in the end of the sleeve. The bushing 27 is provided with a circular head or enlargement 31 at its outer end which fits within a circular flange or rib 32 on the inner side of the adjacent head 15 so as to prevent accumulation of dirt and sand, and the cup 19 at the outer end of the harrow is carried by the hub 28, the lubricant passing through alined 10 radial openings in the hub and the bushing directly to the axle, as clearly shown in Fig. 3.

The spokes are secured upon the tube or sleeve 23 at intervals along the same and to 15 the outer ends of the spokes is secured a spiral blade 33. This blade is formed from tempered steel and has its outer edge beveled to a sharp edge so as to readily cut into the ground and inasmuch as the blade 20 will present a continuous cutting edge to the ground and will rotate as the machine is drawn over the field, the soil will be thoroughly pulverized and placed in proper condition for successful cultivation. The inner 25 face of the blade is flat and it, therefore, penetrates the soil more readily than a blade having a dished or concave surface will penetrate. By reason of having a sharp outer edge and a flat inner face, the blade will 30 penetrate very deeply so that a very deep seed bed can be obtained. Moreover, the flat inner face of the blade will not hold dirt as a dished or concave face does, and, 35 consequently, polishes more readily and remains in operative condition for a longer period than blades heretofore known. The outer extremities of the spokes are offset or turned, as indicated at 34, to conform to 40 the obliquity of the spiral blade and thereby hold the said blade in the proper shape to successfully cut into and turn over and 45 pulverize the soil. The body of each spoke is substantially triangular in cross section, as shown at 35 in Fig. 6, so that the inner 50 face of the spoke will offer no obstruction to the progress of the same and the outer face of the spoke will present an inclined surface to the soil so that it will aid in turning aside that portion of the earth 55 which will be entered by the spoke and the resistance to the forward travel of the machine will be minimized. The spokes are constructed at their inner ends with split hubs or collars having mating flanges 36 60 extending from their split edges to receive clamping bolts 37, whereby they may be effectually clamped around the axle sleeve, as will be readily understood. This construction permits the spokes to be very easily and 65 firmly secured to the axle sleeve and at the same time facilitates the removal of the gang or of any spoke when repairs or replacement may be necessary inasmuch as the withdrawal of the bolts 37 will permit the clamping flanges 36 to be separated and the hub

end of the spoke then easily slipped off the axle tube. The entire gang may be thus quickly removed without disassembling the entire machine.

Mounted upon the draft bar 1 is a seat 70 standard 38 carrying a seat 39, and upon the side of the draft bar is mounted a setting lever 46, the lower end of which is disposed below the draft bar, and links 58 connect the same with brackets 59 on the inner heads 15 75 of the front gangs of the harrow. These gangs are set in the working position by swinging the lever 46 forwardly so that the inner ends of the gangs will be moved rearwardly and the gangs, therefore, set so as to converge rearwardly, as shown by dotted lines in Fig. 1. A spring 60 is secured to the lower portion of the setting lever and to a tension bolt 61 which is mounted upon the under side of the draft bar in advance of the lever to aid in setting the gangs in the inoperative position, the spring being expanded when the lever is swung forwardly to set the gangs and contracting as the lever is released so as to relieve the operator of a considerable portion of the strain involved in bringing the gangs to a position directly across the line of draft, indicated by the full lines in Fig. 1. It will be readily understood that the gangs are given a pivotal 85 movement about the bolts 8 when they are adjusted as described.

The harrow may be drawn over the field by draft animals or by a tractor and when it is to be drawn by a tractor the draft coupling with which tractors are generally equipped may be connected to the coupling plate 64 or directly to the draft bar 1. When the machine is to be drawn by draft animals, it is desirable that the front end of the draft bar be suitably supported so as to relieve the animals, as far as possible, of the weight of the machine and to prevent chafing of their necks and shoulders. For this purpose, the coupling plate 64, which 100 is secured to the lower side of the draft bar at the front end of the same, has its front end engaged between and pivoted to projections 65 on the rear side of a truck 66.

While the soil may be efficiently pulverized by the use of a harrow consisting of a single pair of spiral gangs, I contemplate the employment of tandem gangs, the rear gangs 79 being duplicates, in the construction and arrangement of their parts, of the 110 front gangs but the rear gangs are set to converge forwardly when the machine is in use so that they will cut into the soil in opposition to the cut of the front gangs and the soil will thus be turned in opposite directions so that it will be very thoroughly pulverized and a fine mulch produced. The braces 80 of the rear gangs constitute the draft-applying members thereof and are connected at their front 115 120 125 130

ends to the rear end of the draft bar 1 by a coupling plate 81. To set the rear gangs, I provide a rocking arm or lever 82 which is fulcrumed in the front forked 5 end of a bracket 83 upon the cross bar or beam 84 which is secured to and extends between the braces 80. The lower end of this lever or rocking arm 82 is connected by links 85 with brackets 86 on the inner 10 heads 15 of the front gangs and the upper end of the said lever or rocking arm is connected by links 87 with the brackets 88 on the inner heads of the rear gangs. The links 87 obviously are bent so as to extend 15 downwardly and clear the inner ends of the weight pans or troughs of the rear gangs, and it will be readily understood that when the inner ends of the front gangs are moved rearwardly to bring the 20 said gangs into the working position, the motion will be transmitted through the links 85, the lever 82 and the links 87 so that the inner ends of the rear gangs will be moved forwardly.

25 A link 89 is fitted around the standards of the inner heads of the rear gangs to prevent them moving apart laterally during adjustment.

The ends of the spiral blades are so disposed that they are located at the same circumferential point in all the gangs so that the forward end of a blade enters the ground at the same instant the rear end leaves the ground and the entering ends 35 of all the gangs engage the ground at the same time. Thus, there is always the same length of blade working in each gang and side draft is prevented.

Having thus described the invention, what is claimed as new is:

40 1. A spiral harrow comprising a spiral blade, an axle and spokes, the outer ends of the spokes being disposed obliquely to conform to the shape of the blade and secured thereto and the inner ends of the 45 spokes being formed into split hubs adapted to encircle the axle and be clamped thereto.

2. A harrow comprising a stationary axle, heads secured upon the ends of the axle, means for supplying lubricant to the interior of said heads, bushings disposed adjacent the said heads around the axle and rotatable upon the axle, a tube fitted upon said bushings and extending between the same, means for connecting the sleeve to 55 the bushings whereby the sleeves and bushings will rotate together, a plurality of spokes secured to the sleeve, and a spiral blade carried by the outer ends of the spokes.

3. In a spiral harrow, the combination of 60 a spiral blade, a plurality of spokes supporting said blade, a tube extending from end to end of the spiral blade through the hubs of the spokes, the hubs of the spokes being secured around the said tube, bushings fitted in the ends of the tube and locked to the same and the adjacent spokes, an axle rod extending through the tube and the bushings, heads secured upon the ends of the axle and provided with central lubricating chambers, lubricant holders carried by said heads and communicating with said chambers, and interengaging ribs and recesses upon the heads and the bushings.

70 In testimony whereof I affix my signature.
CHARLES F. MATZ. [L. s.]
